UNITED STATES PATENT OFFICE

2,004,830

PIPE WRENCH

Nelson G. Rector, Jonesboro, Ark.

Application September 7, 1934, Serial No. 743,127

3 Claims. (Cl. 81—64)

The present invention relates to a pipe wrench and has for its prime object to provide a device of this nature which is exceedingly simple in its construction, inexpensive to manufacture, easy to manipulate, adjustable, not likely to injure or mar the pipe, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will hereinafter be more fully described and claimed.

15 In the drawings:

Figure 1 is a side elevation of a wrench embodying the features of my invention.

Figure 2 is a longitudinal section therethrough.

Figure 3 is a plan view thereof.

20 Figure 4 is a sectional view taken substantially on the line 4—4 of Figure 3.

Figure 5 is a detail sectional view through one of the heads on the table.

Figure 6 is a fragmentary plan view showing 25 a head on one end of a strap, and

Figure 7 is a sectional view therethrough.

Referring to the drawings in detail it will be seen that the numeral 5 denotes an elongated handle which is provided at one end with a pair 30 of spaced parallel coextensive flanges 6 the inner faces of which are provided with notches or grooves 7 which incline and open away from said end. These flanges also continue around said end as indicated at 8. Numeral 9 denotes a pair 35 of cables the ends of which are fixed into a pair of heads 10 in a wedge like manner as shown in Figure 5 and these heads are cylindrical in construction and are adapted to be placed in notches 7 as indicated to advantage in Figures 2 and 4.

40 Thus the cable may be disposed tightly about different sized pipes and, referring to Figures 1 and 2 when the handle is swung downwardly or in a clockwise direction the rounded ends of the flange 6 engage the pipe and will cause the tightening of the cables about the pipe, so that the same may be turned.

45 In Figures 6 and 7 I have disclosed a strap 12 having the end thereof wedged in heads 10 as illustrated to advantage in Figure 7 and the strap is usable in the same manner as the cables or flexible members 9.

The end 8 may have teeth 15 as indicated in Figure 1 if so desired.

It is thought that the construction, operation,

utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

5 It will be apparent that changes in the details 10 of construction, and in the combination and arrangement of parts may be resorted to without departing from the spirit or scope of the invention as hereinafter claimed or sacrificing any of its advantages.

15 What is claimed is:

1. A pipe wrench of the class described comprising a handle, a pair of flanges extending from one side only and around one end of the handle, said pair of flanges disposed in spaced coextensive parallelism with each other and provided with spaced aligned notches on the confronting faces of the flanges, a flexible non-articulate member, heads on the ends of the flexible member extending laterally of the member 25 for selectively and detachably seating in aligned notches.

2. A pipe wrench of the class described comprising a handle, a pair of flanges extending from one side only and around one end of the handle, said pair of flanges disposed in spaced coextensive parallelism with each other and provided with spaced aligned notches on the confronting faces of the flanges, a flexible non-articulate member, heads on the ends of the flexible member extending laterally of the member 35 for selectively and detachably seating in aligned notches, and said portion of the flanges extending around the end of the handle being rounded.

3. A pipe wrench of the class described comprising a handle, a pair of flanges extending from one side only and around one end of the handle, said pair of flanges disposed in spaced coextensive parallelism with each other and provided with spaced aligned notches on the confronting 45 faces of the flanges, a flexible non-articulate member, heads on the ends of the flexible member extending laterally of the member for selectively and detachably seating in aligned notches, and the edges of said portion of the flanges extending around the end of the handle being ser- 50

NELSON G. RECTOR.
